WILLIAM VEBER, JR., OF SHINGLE CREEK, NEW YORK.

Letters Patent No. 90,474, dated May 25, 1869.

IMPROVED KNIFE FOR PARING VEGETABLES, &c.

The Schedule referred to in these Letters Patent and making part of the same.

To all whom it may concern:

Be it known that I, WILLIAM VEBER, Jr., of Shingle Creek, in the county of St. Lawrence, and State of New York, have invented a new and improved Vegetable Knife; and I do hereby declare that the following is a full, clear, and exact description thereof, which will enable others skilled in the art to make and use the same, reference being had to the accompanying drawings, forming part of this specification.

This invention relates to improvements in knives, intended to adapt them for paring vegetables, such as have depressions in their surfaces, especially potatoes.

Figure 1 represents a side view of my improved knife, and

Figure 2 represents an edge view of the same.

Similar letters of reference indicate corresponding parts.

In paring with the common knife, it is very difficult to cut out the eyes of potatoes, or rotten spots in apples and other vegetables, without cutting away and wasting considerable portions of the best substance.

To provide an implement to accomplish this without waste, I propose to form the curved bits A B at the end of the common case-knife blade, by which the surfaces of the said depressions may be readily pared, as will be understood without further description.

I am aware of the patent granted to Henry Underwood, August 2, 1864. I claim nothing therein shown as my invention.

What I do claim, and desire to secure by Letters Patent, is—

The vegetable-knife, constructed as described, with the curved bits A B, of unequal lengths, formed in continuation of the edge and back, as herein set forth, for the purpose specified.

The above specification of my invention signed by me, this 18th day of January, 1869.

WILLIAM VEBER, JR.
